UNITED STATES PATENT OFFICE

CARL F. LUNDEBERG, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,124,483.

Specification of Letters Patent. Patented Jan. 12, 1915.

Application filed October 29, 1910. Serial No. 589,675.

To all whom it may concern:

Be it known that I, CARL F. LUNDEBERG, a citizen of the United States, residing in Hartford, in the county of Hartford and 5 State of Connecticut, have invented certain new and useful Improvements in Type-Writing Machines, of which the following is a specification.

This invention relates to platen releases 10 for typewriting machines and is an improvement on the invention disclosed in my application filed August 12, 1910, Serial No. 576,798.

In said application, the platen is illustrated as clutched to the line-space wheel by means of two arms or dogs, which engage the inner periphery of a friction wheel; said dogs pivoted eccentrically to the axis of the wheel, but so that their tips 20 swing in circles nearly coincident with said inner periphery, the pivots being so disposed that the dogs are self-binding; a relative movement between the dogs and the wheel in one direction tending to cause one 25 dog to bite the wheel, and such relative movement in the other direction tending to cause the other dog to bite the wheel.

The present invention relates to a means 30 for releasing the dogs; and it may be used in connection with other kinds of clutches between the line-space wheel and platen. I provide for this purpose two levers, one for each of said dogs, said levers engaging the dogs near their tips, and being pivoted 35 between their ends, and extending to positions close to the platen axle; and upon the platen axle I mount a sliding cone connected to a finger piece, the opposite sides of which cone engage the opposite levers, and 40 operate them simultaneously to release the dogs. The cone is inexpensively made, and on account of its size, is not liable to become worn; and liability of cramping or binding of the parts at the dog-releasing operation 45 is avoided. Said cone or conoidal cam may be so formed, or the ends of the levers may be so beveled, that the platen-releasing finger piece is given a considerable lever- 50 age upon the dogs, so as to render the dog-releasing operation easy.

In the accompanying drawings, Figure 1 is a perspective showing the clutch-releasing mechanism partly broken away, applied to the platen frame of an Underwood writing machine. Fig. 2 is a sectional view,

showing the clutch in action. Fig. 3 shows the clutch released. Fig. 4 is an end view with the cover plate in place. Fig. 5 shows the cover plate removed.

The usual cylindrical platen 1 is fixed on 60 an axle 2 journaled in the ends 3 of a platen frame.

An annular line-space wheel 4, having a drum 5, is loosely mounted on a cup-like member comprising a disk 6, fast on the 65 axle 2. The wheel 4 is usually turned step-by-step by means of a lever 7, operating through a slide 8 and pawl 9, and is held by the usual detent 10.

An arm or dog 11, pivoted on the disk 6 70 eccentrically thereof by means of a pivot 13 on the disk, is pressed by a spring 14 toward the left to cause its outer end to bear forcibly against the drum 5 to bind the wheel to the platen. A second arm or 75 dog 11 also mounted on the pivot 13, is pressed by the same spring toward the right, to wedge against the drum 5 in the opposite direction. These dogs prevent relative turning of the platen and line-space 80 wheel. The outer ends of the dogs may be provided with shoes 29 as in the former application.

The platen is freed from the spacing-wheel by pressing inwardly on a button or 85 finger piece 15, connected to a head 16 by rods 17 passing loosely through the hand wheel 18. This forces an axially-sliding cone or wedge 19 on said head, against the inner ends of levers 20, to swing the outer 90 ends 27 of said levers against said clutch dogs 11 and cast them off from the drum 5. The outer ends of said releasing levers are formed with fingers 27 which project through slots 23 in a cap 22 to operate the 95 dogs.

The levers are pivoted at 21 on the cap 22 fastened to flange 28 on the disk 6, their inner ends engaging opposite sides of the conoidal wedge 19, and having lips 24 100 which may be sharply beveled, as at 25, to secure ease of operation of the releasing mechanism.

Upon releasing the button 15, a spring 26 returns the head 16, with the cam 19, whereupon the spring 14 again forces the dogs 11 against the line-space wheel.

It will be noticed that the levers 20 operate to transmit the pressure of the axially sliding wedge or cam to the dogs at a point 110

remote from the pivotal points of said dogs to release the platen. By mounting the wedge on the axle a compact structure is obtained and the resistance of one releasing lever to the wedge is opposed to the other, to prevent its binding on the axle.

5 Variations may be resorted to within the scope of the invention.

Having thus described my invention, I 10 claim:

1. In a typewriting machine, the combination with a line-spacing wheel, platen and platen axle, said platen and axle being rotatable relatively to said line-spacing wheel, 15 of dogs connected with the platen and normally pressed against the line-spacing wheel, levers, the outer ends of which engage the dogs near their outer ends, and a wedge pressed between the inner ends of said levers 20 to release the dogs.

2. In a typewriting machine, the combination with a line-spacing wheel, platen and platen axle, said platen and axle being rotatable relatively to said line-spacing wheel, 25 of dogs connected with the platen and normally pressed against the line-spacing wheel, levers, the outer ends of which engage the dogs near their outer ends, and a wedge pressed between the inner ends of said levers 30 to release the dogs, the inner ends of said levers being beveled.

3. In a typewriting machine, the combination with a line-spacing wheel, platen and platen axle, said platen and axle being rotatable relatively to said line-spacing wheel, 35 of a clutch mechanism including a dog engaging the line-spacing wheel, to connect the spacing wheel and platen, an apertured cap for said clutch mechanism, a releasing lever 40 pivoted to the cap, the outer end of the lever projecting through the aperture to engage the dog, and an axially slideable cam pressed against the inner end of the lever.

4. In a typewriting machine, the combination with a line-spacing wheel, platen and platen axle, said platen and axle being rotatable relatively to said line-spacing wheel, 45 of a clutch mechanism including a dog engaging the line-spacing wheel, to connect the spacing wheel and platen, a cam sliding on the axle, a finger piece controlling the cam, and a lever, one end of which is engaged by 50 the cam to press the opposite end against the free end of the dog to release the clutch.

5. The combination with a platen and a line-space wheel, of a platen axle, a drum upon said line-space wheel and having a smooth periphery, a pair of pivoted self-binding dogs having ends or bits which frictionally engage said smooth periphery, a pair of releasing levers, one for each of said dogs, and means movable upon the platen axle to operate said levers.

6. The combination with a platen and a 65 line-space wheel, of a platen axle, a drum

upon said line-space wheel and having a smooth periphery, a pair of pivoted self-binding dogs having ends or bits which frictionally engage said smooth periphery, a pair of releasing levers, one for each of said dogs, and a cam having a finger-piece and 70 slideable upon the platen axle to engage and operate said levers; said levers engaging said dogs near the tips of the latter, and extending close to said platen axle to be 75 engaged by said cam.

7. In a typewriting machine, the combination with a platen, of a line-space wheel for said platen, a pair of pivoted dogs for connecting said line-space wheel and said platen so that they will rotate in unison, a pair of levers arranged to rock in a plane at right angles to the axis of said platen, and means moving in the longitudinal direction of the axis of said platen for rocking said 80 levers; said levers having out-turned ends to engage said means and inturned ends to engage said dogs.

8. The combination with a platen, a platen axle, and a line-space wheel having a flange 90 thereon, of means forming a casing on which the line-space wheel is mounted for rotation relatively to the platen, clutch dogs within said casing and movable into and out of frictional contact with said wheel, levers 95 pivoted on said casing and extending into position to operate the clutch dogs, and means located outside the casing to actuate said levers.

9. In a typewriting machine, the combination with a platen, of a line-space wheel for said platen, a pair of self-binding pivoted friction-dogs for connecting said line-space wheel and said platen so that they will rotate in unison, releasing means arranged 100 near the platen axis and movable in the longitudinal direction of said axis, and a pair of levers for actuating said dogs, the inner ends of said levers lying in the path of said releasing means, whereby said levers 110 are simultaneously rocked, and the opposite ends of said levers engaging the outer ends of said dogs to swing them out of connection with said line-space wheel.

10. The combination with a roller platen and a line-space wheel, of a clutch comprising a clutch dog connecting said line-space wheel to said platen, a casing inclosing said dog, releasing means concentric to the platen axis and movable longitudinally thereof, exterior to said casing, and a separate lever arranged to rock freely between said dog and the releasing means to operate the former by the latter, one end of said lever lying in the path of movement of said releasing means, and its other end engaging said dog to press it out of connection with said line-space wheel.

11. The combination with a roller platen and a line-space wheel, of a clutch compris- 130

ing a pair of clutch dogs connecting said line-space wheel to said platen, a casing enclosing said dogs, releasing means concentric to the platen axis and movable longitudinally thereof, exterior to said casing, and a pair of separate levers arranged respectively to rock freely between said dogs and the releasing means to operate the former by the latter, corresponding ends of 10 said levers lying in the path of movement of said releasing means, and their other ends respectively engaging said dogs to press them out of connection with said line-space wheel.

15 12. The combination with a platen and a line-space wheel, of pivoted clutch dogs connecting said line-space wheel with said platen, releasing means movable longitudinally of the platen axis, and levers operable 20 reversely to said dogs to actuate the latter, said levers rocking oppositely to the movement of said releasing means to disconnect said dogs from said line-space wheel.

13. The combination with a platen, an 25 axle therefor, and a line-space wheel revolvable relatively to said platen, of a friction-clutch comprising a pair of self-binding dogs pivoted each at one end and outwardly engaging said line-space wheel at their opposite ends, releasing means arranged near the platen axle, and a pair of levers intermediate said releasing means and dogs to actuate the latter at their outer ends, the inner ends of said levers being engaged by 35 said releasing means to rock said levers, to press the dogs out of their clutch engagement.

14. The combination with a platen, an 40 axle therefor, and a line-space wheel revolvable relatively to said platen, of a friction-clutch comprising a pair of self-binding dogs pivoted each at one end and outwardly engaging said line-space wheel at their opposite ends, releasing means comprising a 45 wedge slideable longitudinally of the platen axis and arranged near said axle, and a pair of pivotal levers intermediate said releasing means and dogs to actuate the latter, said levers being engaged at their inner ends by

said wedge and rocking in a plane transverse to the movement of said wedge, whereby said levers are caused at their outer ends to press the dogs inwardly out of clutching engagement.

15. The combination with a platen, an 55 axle therefor, and a line-space wheel revolvable relatively to said platen, of a clutch comprising a dog pivoted at one end and engaging said line-space wheel at its opposite end, a pivotal lever having one end engaging 60 with said dog to release the latter, the planes of movement of said dog and lever being parallel to each other and transverse to the platen axis, and means movable longitudinally of the platen axle to actuate said lever, 65 the other end of said lever being in the path of said means to be engaged thereby.

16. The combination with a platen, an 70 axle therefor, and a line-space wheel revolvable relatively to said platen, of a clutch comprising a pair of dogs pivoted each at one end and engaging said line-space wheel at their opposite ends, a pair of pivotal levers each respectively engaging at one end 75 with a dog to release said dogs, the planes of movement of said dogs and levers being parallel to each other and transverse to the platen axle, and means movable longitudinally of the platen axle to actuate said levers, the other ends of said levers being in the path 80 of said means to be engaged thereby.

17. The combination with a platen, an 85 axle therefor, and a line-space wheel revolvable relatively to said platen, of a pair of pivotal dogs movable in a plane transverse to the platen axis into engagement with said line-space wheel, pivotal levers movable in a plane parallel with the plane of movement of said dogs to engage the dogs at points 90 distant from their fulcrums, and means movable transversely of said levers to rock them, causing said levers to thereby release said dogs from clutching engagement with said line-space wheel.
